UNITED STATES PATENT OFFICE

159,125

ADVERTISING PENCIL

Joseph V. Wuestman, Unionville, N. J.

Application August 29, 1947, Serial No. 141,108

Term of patent 14 years

(Cl. D74—24)

To all whom it may concern:

Be it known that I, Joseph V. Wuestman, a citizen of the United States, residing at Unionville, in the county of Union and State of New Jersey, have invented a new, original, and ornamental Design for an Advertising Pencil, of which the following is a specification, reference being had to the accompanying drawings, forming a part thereof.

In the drawings:

Fig. 1 is an elevational view; Fig. 2 is another elevational view observed from the side in Fig. 1 but inverted; and Fig. 3 is a cross-sectional view, taken on line 3—3 in Fig. 1, hatched conventionally to show the transparency of the sectioned portion, said views showing an advertising pencil embodying my new design.

The characteristic feature of the design resides in the transparent portion and adjacent opaque portion in the barrel and in the presence of a mov-

able object within the barrel, exemplified in dotted lines in the drawings, which appears in the transparent portion in one position of the pencil and disappears within the opaque portion in a reversed position of the pencil.

I claim:

The ornamental design for an advertising pencil, as shown and described.

JOSEPH V. WUESTMAN.
